UNITED STATES PATENT OFFICE.

HAROLD ROWNTREE, OF SCARSDALE, NEW YORK, ASSIGNOR TO NATIONAL PNEUMATIC COMPANY, OF NEW YORK, N. Y., A CORPORATION OF WEST VIRGINIA.

ELECTRICALLY-OPERATED DOOR.

Application filed October 4, 1924. Serial No. 741,698.

This invention relates to the electrical operation of doors and more particularly to that class of doors, the automatic operation of which is dependent upon the approach of a person into the immediate vicinity of the door.

The primary object of the invention is to automatically control the electrical operation of doors in a simple, compact and thoroughly efficient manner through the utilization of mechanism not liable to derangement and capable of long continued use.

A further object of the invention is to provide electrical door opening means adapted to employ as a prime mover a non-reversible motor.

Well built and practical small direct current motors and alternating current motors, which are only built to operate in one direction are readily attainable at very reasonable prices, but small motors which are reversible are difficult and expensive to obtain and are liable to derangement. It is only in the larger sizes apparently that a reversible motor becomes really practicable. By using a one direction motor, I am able to use a small cheap motor and thus reduce the initial cost of installation and minimize in subsequent operating costs.

Another object of the invention is to provide a novel form of control device which, in the preferred practical form of the invention, consists in a platform or treadle suspended in such manner that the imposition of a relatively light pressure thereon will effect the opening of the associated door. The platform suspension embodies pronounced novelty and renders the installation very sensitive. The control of the door opening mechanism is effected through electric circuits including switch mechanism directly operated by movement of the platform.

Of considerable importance is the particular method employed in supporting or suspending the platform. In the preferred embodiment of the invention, this suspension is accomplished by hanging the four corners of the platform from links supported on the short arms of levers of the first class, the long arms of the levers being provided with adjustable weights, through the regulation of which the platform may be substantially counterbalanced and made sufficiently sensitive to operate under very slight pressures.

With this lever suspension is associated a switch mechanism, the parts being so arranged that normally open circuits result but are adapted to be momentarily closed when it is desired to effect the operation of the door. This arrangement minimizes current consumption and consequent operating costs.

Another object of the invention is to provide a simple, compact and highly efficient mechanism for imparting movement to the doors. This mechanism may be mounted either above or below the doorway and is actuated by an electric motor which constitutes the prime mover and is controlled, in turn, by the suspended platform to which I have referred. The operating mechanism under consideration is such as to permit of the employment of a non-reversible motor as a prime mover and is automatic in that it will automatically choose the opening and closing operations of the door. The structure is such, moreover, that it will not get out of order and will remain serviceable indefinitely.

The present invention may be employed to effect the automatic operation of doors from either one side thereof only or from both sides thereof, and while particularly adapted to be automatically controlled by the approach or departure of a person to and from proximity with the door, this absolutely automatic operation may be omitted and the door opening and closing mechanism controlled by a manually operable switch, depending of course upon the particular environment in which the invention is employed. In this connection, it is to be noted that the invention is capable of general application. For example, it may be employed to operate the doors of a building or the doors of street cars, or, for that matter, in any other connection.

Further objects of the invention will appear more fully hereinafter.

The invention consists substantially in the construction, combination, location, and relative arrangement of parts, all as will be more fully hereinafter set forth, as shown by the accompanying drawings and finally pointed out in the appended claims.

Referring to the drawings:

Figure 1 is a plan view of door operating mechanism.

Figure 2 is a like view illustrating the manner in which the operating mechanism is connected to one of the doors which it actuates.

5 Figure 3 is an elevation of the structure shown in Figure 1 with certain parts illustrated in section and the motor and universal joint, shown in Figure 1, eliminated from this figure in the interest of clearness.

10 Figure 4 is a section on the line 4—4 of Figure 3.

Figure 5 is a wiring diagram of electrical connections which are, in practice, associated with the mechanism shown in the preceding 15 figures.

Figure 6 shows a modified form of wiring diagram.

Figure 7 illustrates a four part folding door with the present invention associated 20 therewith.

Figure 8 is a diagrammatic illustration of the connections between the door operating mechanism and the doors.

Figure 9 is an enlarged detail of a portion 25 of the showing of Figure 7.

Figure 10 is a side elevation of a platform or treadle by means of which the door opening mechanism is controlled; and,

Figure 11 is an enlarged fragmental elevation of a portion of the structure shown in 30 Figure 10.

The door to be operated is indicated in Figures 7 and 9 of the drawings as a double 35 two part folding door 1, although it will be understood that the present invention may be associated with any ordinary or desired form or type of door. In the showing of the drawings, each of the double doors are composed of two sections 2 and 3. As usual 40 they are pivoted to one another while one section of each door is mounted for pivotal movement on a vertical shaft 4. To one end of each of these shafts is secured a suitable operating arm 5 shown best in Figure 2 and 45 movement is transmitted to the doors through these operating arms by mechanism next to be described.

Referring now particularly to Figures 1 to 50 4 inclusive, 6 designates a small electric motor which serves as a prime mover for the door operating mechanism. This motor may be of any suitable make and is preferably of a non-reversible type, being adapted at all times to operate in one direction. The 55 armature shaft 7 of the motor is connected through a universal joint 8 with a stub shaft 9 on which is fixed a worm 10. The stub shaft 9 is journaled within suitable bearings forming part of the bracket 11, and this 60 bracket also provides a bearing for a second stub shaft 12, arranged at substantially ninety degrees to the axis of the shaft 9.

On the shaft 12 is fixed a worm wheel 13, which meshes with the worm 10 and fixed 65 with respect to the worm wheel 13 is a bevel

gear 14, so that power from the motor 6 is communicated through the driving connections described to the bevel gear 14.

Extending in substantially parallel relation to the shaft 9 and spaced laterally therefrom is a shaft 15 on which is mounted two bevel gears 16 and 17, so positioned that they are adapted, at all times, to mesh with the bevel gear 14 at opposite sides thereof, to the end that, when the gear 14 is operated 70 the bevel gears 16 and 17 will be simultaneously rotated but in opposite directions with respect to one another.

Both of the gears 16 and 17 are loose on the shaft 15, but are adapted to drive said 75 shaft in corresponding directions through friction disk connections therewith. Thus the gear 16 has rigid therewith a friction disk 18, while a similar friction disk 19 is rigid with the gear 17. A friction disk 20 80 cooperates with the disk 18, while another disk 21 cooperates with the disk 19. The disk 21 has a hub or boss fixed to the shaft by a pin 22, while the disk 20 has a hub or boss which has a feather connection with the 85 shaft to lock said disk and shaft against relative rotation. Adjusting and locking nuts 23 are however associated with the shaft 15 and are adapted to act against the end of the boss of the disk 20, so that any lost 90 motion between the friction faces of the respective disks may be taken up.

Fixed to one end of the shaft 15 is a collar 24 and a spring 26 is coiled about the shaft between the collar 24 and a bearing 25, 100 to normally impell the shaft in a direction to bring the friction disk 21 into gripping relation with its cooperating disk 19 and to simultaneously move the disk 20 free from driven relation with respect to its cooperating disk 18.

However, if the shaft 15 is moved to the right against the tension of the spring 26, it will be apparent that the disk 20 will be 105 shifted into driven relation with the disk 18 while the disk 21 will be moved free from driven relation with respect to the disk 19.

This longitudinal shifting of the shaft against the tension of the spring is accomplished by a solenoid 27 and, as best shown in Figure 3, the core 28 of this solenoid is connected to a lever 29, one end of which is pivoted at 30 and the other end of which is connected by a link 31 to an arm 32 pivoted at 33 to a fixed bracket. The arm 32 is tapped intermediate its ends and an adjusting screw 34 threads through the said 115 tapped opening and is adapted to bear against the left hand end of the shaft 15.

The normal position of the parts is as shown in Figure 3, wherein it will be noted that the spring 26 has moved the shaft 15 to the extreme left and retracted the core of the solenoid. The parts will remain in these 120 relative positions until the solenoid is en-

ergized, whereupon its core will be drawn in and through the link and lever connections described will shift the shaft 15 to the right to effect a reversal of the direction of rotation of said shaft.

To the right hand end of the shaft 15, as shown in Figure 3, is fixed a bevel gear 35, which meshes with a bevel gear 36 mounted for rotation on a stud 37. On the under side of one half of this bevel gear 36 is attached an insulated friction strip 38 of conducting material with which three contacts 39, 40 and 41 normally engage. The contact strip 38 is arcuate in form and is of such length that as the gear 36 is rotated by the gear 35, the contacts 39 and 41 are adapted to ride free of the opposite ends of the contact strip, as the gear 36 approaches the terminus of its travel, whereas the control contact 40 is adapted to engage with said strip at all times. The purpose of these contacts will be hereinafter fully disclosed.

The mechanism shown in Figures 1 and 3 is mounted in any suitable relation to the vertical operating shafts 4 of the doors and while said mechanism may be mounted either above or below the doors it is shown for the purpose of illustration in the former position, as will be seen by reference to Figure 7.

Connections are made between the operating arms 5 of the respective door shafts 4 by means of links 42, one end of each link being connected to one of the operating arms 5, while the other end of each link is secured to a wrist pin 43 carried by the gear 36, as is clearly shown in Figures 1 and 2 and diagrammatically illustrated in Figure 8.

When the parts are connected in the manner specified, rotation of the gear 36 in one direction will effect the opening of the doors while rotation of such gear in a counter direction will effect the closing thereof. The direction of rotation of the gear will, manifestly, be dependent upon the condition of the solenoid 27 since if the solenoid is energized the gear will be rotated in one direction, while if it is not energized the gear will be rotated in the opposite direction.

The energizing of the solenoid as well as the feed of current to the motor 6 may be controlled in various ways. For example, it may be controlled by the approach of a person into the immediate vicinity of the door or it may be controlled through the manual operation of a switch. These two specified methods have been illustrated in the drawings and the former will now be described.

In this connection, attention is directed to Figures 10 and 11 of the drawings, which illustrate a novel form of platform or treadle, so constructed that when the weight of a person is imposed thereon, as for ex-

ample by the approach of such person into the immediate vicinity of the door, movement will be imparted to the platform for the purpose of closing an electric circuit to initiate the operation of the door opening mechanism.

Referring to these figures, 44 designates a rectangular platform which, in the embodiment of the invention shown, is adapted to underlie the door and to project beyond both sides thereof, said platform being provided at each end with hinged flaps 45 to allow a person to conveniently mount the platform or leave the same.

At each of its four corners, a platform is suspended on a link 46, the upper end of each link being connected to the short arm of a lever 47. The lever is fulcrumed at 48 on a stationary fulcrum and on the long arm of each lever is mounted a weight 49 adapted to be slid longitudinally of the lever in order to obtain proper counterbalancing and provided with suitable means for maintaining it in adjusted position. A stop 50 is preferably associated with the lever to limit the upward movement of the long arm thereof. At the extreme end of the long arm is a contact shoe 51 and with this shoe three contact leaves 52, 53 and 54 are associated. The contact leaves are so positioned that when the long arm of any lever is elevated, all of said contact leaves will be in engagement with the shoe 51, whereas all of said leaves will be disengaged from the shoe when the long arm of said lever is depressed.

In practice, the weights 49 are so adjusted that, under normal conditions, these weights will overbalance the weight of the platform 44, so that the long arms of the levers will be normally lowered while the platform will be in raised position as shown in Figure 10. The adjustment is however sufficiently sensitive that as soon as a person steps upon one of the flaps 45, at least one corner of the platform will become overbalanced and will be depressed to raise the long arm of the corresponding lever and cause the shoe 51 to approach the contact fingers or leaves 52, 53 and 54. These contact fingers constitute part of an electrical control circuit, a wiring diagram of which is shown in Figure 5.

It will be noted from Figure 5 that the lever shoes 51 at the four corners of the platform are in multiple, so that when any corner of the platform is depressed, the following circuit is immediately established. From a source of power 55, current is fed through any suitable cut off switch 56 to the contact 52, thence through one of the shoes 51 to contact 53 and from contact 53 to contact finger 39, thence through contact strip 38 and contact finger 40 through the motor 6 and from the motor 6 to ground at 57. Simultaneously with the completion of this circuit, a second circuit is completed from

the shoe 51 through contact 54 to the solenoid 27 and thence to ground at 57. As soon as the solenoid is energized, its core is drawn in and said core carries with it a bridge piece 58 which is adapted to normally engage two contacts 59 and 60 mounted at the rear end of said solenoid. The drawing in of the core 28 of the solenoid, when said solenoid is energized, will cause the lever and link connections, which have been hereinbefore described, to shift the shaft 15 longitudinally and effect rotation of said shaft through the driven engagement of the friction disk 20 with the disk 18, so that the operation of the motor 6 will be transmitted to the door operating gear 36 in a direction to effect the opening of the door.

As the door moves open, the contact strip 38 is shifted around with the bevel gear 36 to which it is attached until the end of the strip passes from under the contact 39, which operation takes place shortly before the door is wide open. As soon as the contact 39 leaves the strip 38, the circuit through the motor is broken and the motor de-energized, but so long as any one of the treadle shoes 51 are in engagement with their contact springs, the solenoid will remain energized and the door will remain open. As soon, however, as pressure is released from the treadle to allow it to assume its normally raised position, the solenoid circuit will be immediately broken, whereupon the tension of the spring 26 will become effective to shift the shaft 15 to the left and in so doing will retract the core of the solenoid 27 with the result that the bridge piece 58 will bridge the contacts 59 and 60. The following circuit will thereupon be established.

From the source 55, through switch 56, contact 59, bridge piece 58, contact 60, switch arm 41, contact strip 38, contact 40, motor 6 and to ground at 57. The motor is immediately energized and revolves in the same direction as before, but, inasmuch as the solenoid 27 remains de-energized, power will be transmitted from the friction disk 21 to the disk 19 with the result that the door operating gear 36 will be rotated in the opposite direction and the door will be closed.

Shortly before the door arrives at a fully closed position, the contact 41 moves free from the end of the contact strip 38 and the circuit of the motor is broken, whereupon the door stops when it is closed.

It will be apparent that when the door is in a closed and idle condition that all of the circuits are de-energized or dead. This is an important practical consideration since there is no waste of current, current only being used when door operations are actually taking place.

The operations of the platform to which I have referred are those which result from

the passage of a person through a doorway. As the person enters the vicinity of the doorway, he does so by way of the treadle and he traverses the treadle until he has passed through the doorway and leaves the treadle at the opposite end thereof. The operation is therefore entirely automatic.

In practice, the platform may, if desired, be installed substantially flush with the floor and inasmuch as movements of the platform are multiplied through the long leverage connections described, such movements are barely perceptible, if noticeable, to a person walking upon the platform. The leverage suspension is moreover housed in concealed position.

The construction which I have described is highly advantageous because of the freedom from complications that have upset all previous attempts at electrical operation of doors. Complicated motor design is not required and the structure is simple and compact and not liable to derangement.

The control as described is particularly applicable to the automatic control of folding doors for passageways, depots, stations or elsewhere where a large number of people are frequently passing. The invention, however, is also readily susceptible to many different uses and may be employed to advantage on street cars in lieu of the customary pneumatic door controls, in which environment it would have some decided advantages, among which may be mentioned the relief of the air compressor from a portion of the work it has hitherto been required to do.

When used on a street car, the present invention may, or may not, embody the automatic treadle or platform which I have described. If used with the platform, said platform would preferably be placed only on the inside of the door, so that a person wishing to leave the car and standing on the platform would automatically cause the opening of the door, the door serving to automatically close as soon as the person steps off of the car. In such a construction, the door could not manifestly be opened from the outside, but only from the inside as specified.

In adapting the invention to street cars, it may be desirable to eliminate the platform entirely and to use in lieu thereof a control handle. Such an arrangement is illustrated in Figure 6 of the drawings.

From the wiring diagram of Figure 6, it will be noted that substantially the same arrangement is present as is illustrated in Figure 5 except that a controller or switch is substituted for the platform contacts and that the contacts 59 and 60 and the bridge piece 58 shown in Figure 5 at the back of the solenoid are omitted. Moreover, an air control switch, not employed in the construction of Figure 5, is shown in the con-

struction of Figure 6. It may be stated with regard to these modifications and omissions that the solenoid switch is not necessary in connection with this circuit, as the circuit for closing the door passes through the hand control switch when it is desired to close the door. The function of the circuits shown in Figure 6 may be briefly described as follows.

- 10 When it is desired to open the door, the controller lever 57^a which corresponds in its function to the shoe 51 is manually moved into engagement with the contact 52^a to establish a circuit from the source 55 through 15 cut out switch 56 to a contact 53^a, thence through controller 57^a to contact 52^a, thence to contact 39, through strip 38 and contact 40, to the motor 6, whence it passes to ground at 57. As a result the motor is energized 20 and the door opened through mechanism of the character shown in Figures 1 and 3. If it is desired to have the control so arranged that the door could not be opened unless the car be stopped, this can be arranged in any 25 suitable way, such, for example, as by including the air switch 61 in the wire connection between the contact 52^a and the contact 39. Such an air controlled switch could be connected to the air pipe line of the car 30 braking system, so that when the brakes of the car are applied, the air pressure will be communicated to the switch 61 to cause the bridge piece 62 to bridge contacts 63 and 64 and enable the completion of the circuit 35 which I have described through operation of the controller handle. A spring 65 will serve to normally retract the bridge piece and preclude the completion of such circuit when the brakes of the car are not applied.
- 40 After a door has been opened in the manner described to permit the entrance or exit of a passenger, it may be subsequently closed by shifting the controller to engage with the contact 54^a, whereby the following circuit 45 is completed.

From source 55 through cut out switch 56 to contact 53^a, controller 57^a, contact 54^a, contact 41, contact strip 38, contact 40, motor 6 and to ground at 57. This circuit does not include 50 the solenoid and consequently the operations of the motor will effect the closing of the door. In this connection it may be noted that the door can be closed even if the car had started while it was open, since the door closing circuit does not include the air switch 61.

Having thus fully described the invention, what I claim as new and desire to secure by Letters Patent is:

- 60 1. In a door operating mechanism, the combination with a door, of power mechanism for moving the door, an electric motor for operating the power mechanism, an electric circuit including the motor and also including a plurality of normally open

switches arranged in multiple, each of said switches including a lever, a treadle suspended on said levers and overbalanced thereby to normally maintain all of the switches in open condition, said treadle being depressible when weight is imposed thereon for the purpose of actuating one or more of the levers to effect the closing of the corresponding switch or switches.

2. In a door operating mechanism, the combination with a door, of power mechanism for moving the door, an electric motor for operating the power mechanism, an electric circuit including the motor and also including a plurality of normally open switches, each of said switches including a lever, a treadle extending beyond the opposite sides of the door and supported in normally raised position by the levers with all of the switches in open condition, said treadle being depressible, when weight is imposed thereon, for the purpose of actuating one or more of the levers to close a corresponding number of switches.

3. In a door operating mechanism, the combination with a door, of power mechanism embodying a door moving element connected with the door, a non-reversible electric motor, treadle operated means for controlling the operations of the motor, reversible driving connections between the motor and the door moving element, and means for automatically reversing said connections to alternately open and close the door upon the successive operations of the motor said automatic reversing action being controlled by said treadle operated means.

4. In a door operating mechanism, the combination with a door, of power mechanism embodying a door moving element operatively connected with the door, a shaft for imparting rotation to the door operating element, a non-reversible electric motor, means for controlling the operations of the motor, reversible driving connections between the motor and the shaft, treadle operated means to automatically condition the driving connections to drive the shaft in one direction to open the door, and means to automatically condition the driving connections to drive the shaft in the opposite direction to close the door, said automatic conditioning action being produced by said treadle operated means.

5. In a door operating mechanism, the combination with a door, of a door moving element operatively connected thereto, a shaft geared to said element and adapted to rotate the same, friction disks fixed in spaced relation on said shaft, a pair of bevel gears positioned between said disks and having friction faces adapted to cooperate with the friction disks, said gears being mounted to rotate loosely on the shaft, a non-reversible electric motor, a bevel pinion positioned be-

- tween and meshing with said gears, operative connections between the bevel pinion and the motor, whereby when the motor is operated, the pinion serves to simultaneously drive both gears in opposite directions, means for normally impelling the shaft in one direction to bring one of the friction disks thereof into driven relation with one of the gears to effect movement of the door 10 in one direction, means for shifting said shaft in the opposite direction to disengage the last mentioned disk and engage the other disk with its cooperating gear for the purpose of reversing the rotation of the shaft 15 and moving the door in the opposite direction, and electric connections including the motor, and also switch mechanism for initiating and timing the operations of the motor and automatically controlling the direction of rotation of the shaft.
6. In a door operating mechanism, the combination with a door, of a door moving element operatively connected thereto, a shaft geared to said element and adapted 20 to rotate the same, friction disks fixed in spaced relation on said shaft, a pair of bevel gears positioned between said disks and having friction faces adapted to cooperate with the friction disks, said gears being 25 mounted to rotate loosely on the shaft, a non-reversible electric motor, a bevel pinion positioned between and meshing with said gears, operative connections between the bevel pinion and the motor, whereby when the motor is operated, the pinion serves to simultaneously drive both gears in opposite directions, means for normally impelling the shaft in one direction to bring one of the friction disks thereof into driven relation with one of the gears to effect movement of the door 30 in one direction, electromagnetic means for shifting said shaft in the opposite direction to disengage the last mentioned disk and engage the other disk with its cooperating gear for the purpose of reversing the rotation of the shaft and moving the door in the opposite direction, and electrical connections embodying switch mechanism adapted when shifted to complete a circuit through the motor while the door is closed, to energize the motor for the purpose of opening the door, and a cut off device also included in said electrical connections to automatically de-energize the motor when the door has been opened, and a switch also 35 included in said electrical connections and adapted when closed to re-energize the motor for the purpose of closing the door, said cut off device being adapted to again de-energize the motor when the door has been closed.
7. In a door operating mechanism, the combination with a door, of a door moving element operatively connected thereto, a non-reversible motor, reversible driving connections between the motor and the door moving element, electromagnetic means for controlling the driving direction of the driving connections, and electrical connections including the motor, said electromagnetic means, and treadle operated switch mechanism adapted to control the operations of the motor and said electro-magnetic means.
8. In a door operating mechanism, the combination with a door, of a door moving element operatively connected thereto, a non-reversible motor, reversible driving connections between the motor and the door moving element, electromagnetic means for controlling the driving direction of the driving connections, and electrical connections including the motor, said electromagnetic means, and switch mechanism adapted to control the operations of the motor, and said electrical connections also including a normally open switch, the closing of which is caused by the application of air to the air brakes of the car.
9. In operating mechanism for car doors, the combination with a door, of a door moving element operatively connected thereto, a non-reversible motor, reversible driving connections between the motor and the door moving element, electromagnetic means for controlling the driving direction of the driving connections, and electrical connections including the motor, said electromagnetic means and switch mechanism adapted to control the operations of the motor, and said electrical connections also including a normally open switch, the closing of which is caused by the application of air to the air brakes of the car.
10. In operating mechanism for car doors, the combination with a door, of a door mov-

relation on said shaft, a pair of bevel gears positioned between said disks and having friction faces adapted to cooperate with the friction disks, said gears being mounted to rotate loosely on the shaft, a non-reversible electric motor, a bevel pinion positioned between and meshing with said gears, operative connections between the bevel pinion and the motor, whereby when the motor is operated the pinion serves to simultaneously drive both gears in opposite directions, means for normally impelling the shaft in one direction to bring one of the friction disks thereof into driven relation with one of the gears to effect movement of the door in one direction, electromagnetic means for shifting said shaft in the opposite direction to disengage the last mentioned disk and engage the other disk with its cooperating gear for the purpose of reversing the rotation of the shaft and moving the door in the opposite direction, and electrical connections embodying switch mechanism adapted when shifted to complete a circuit through the motor while the door is closed, to energize the motor for the purpose of opening the door, and a cut off device also included in said electrical connections to automatically de-energize the motor when the door has been opened, and a switch also included in said electrical connections and adapted when closed to re-energize the motor for the purpose of closing the door, said cut off device being adapted to again de-energize the motor when the door has been closed.

8. In a door operating mechanism, the combination with a door, of a door moving element operatively connected thereto, a non-reversible motor, reversible driving connections between the motor and the door moving element, electromagnetic means for controlling the driving direction of the driving connections, and electrical connections including the motor, said electromagnetic means, and treadle operated switch mechanism adapted to control the operations of the motor and said electro-magnetic means.

9. In operating mechanism for car doors, the combination with a door, of a door moving element operatively connected thereto, a non-reversible motor, reversible driving connections between the motor and the door moving element, electromagnetic means for controlling the driving direction of the driving connections, and electrical connections including the motor, said electromagnetic means and switch mechanism adapted to control the operations of the motor, and said electrical connections also including a normally open switch, the closing of which is caused by the application of air to the air brakes of the car.

10. In operating mechanism for car doors, the combination with a door, of a door mov-

ing element operatively connected thereto, a non-reversible motor, reversible driving connections between the motor and the door moving element, electromagnetic means for controlling the driving direction of the driving connections, and electrical connections embodying a circuit including a treadle operated switch, an automatic cut off switch for the motor, a second circuit including the treadle operated switch and the electromagnetic means, and a third circuit including the motor, the cut off switch, and an additional switch operable by the electromagnetic means, whereby the closing of the treadle switch will cause the motor to oper-

ate until it is de-energized by the automatic cut off switch, while the opening of the treadle switch will cause the motor to again function until it is again de-energized by the cut off switch, said cut off switch being automatically controlled by the position of the door to de-energize the motor at the conclusion of the door opening operation and at the conclusion of the door closing operation.

In testimony whereof I have hereunto set my hand on this 30th day of September, A. D., 1924.

HAROLD ROWNTREE.
